Filed Apr. 5, 1962, Ser. No. 69,591

Term of patent 14 years

(Cl. D58—5)

FIGURE 1 is a side elevation of a jug showing our new design;

FIGURE 2 is a rear elevation thereof;

FIGURE 3 is a front elevation thereof; and

FIGURE 4 is a cross-sectional view thereof taken on line 4-4 of FIGURE 1.

The essential feature of our design resides in the combination on the upper portion of a jug of the configuration shown of a handle and underlying area having the specific configuration shown.

We claim:
The ornamental design for a jug, as shown and described.
